SPRING CONSTRUCTION

Rutherford Y. Millar, Oakland, Calif., assignor to
 National Automotive Fibres, Inc., Detroit,
 Mich., a corporation of Delaware

Application September 25, 1939, Serial No. 296,475

8 Claims. (Cl. 155—179)

The present invention relates to spring construction and more particularly to a spring construction embodying leaf springs and characterized by relatively small thickness.

It is an object of the present invention to provide a spring construction having a plurality of outwardly bowed leaf springs in combination with other resilient means tending to resist flexing of said leaf springs in a direction to reduce the amount of bow.

A further object of the present invention is to provide outwardly bowed leaf springs having a coil spring associated at each end thereof, said coil spring adapted to urge the ends of said leaf springs toward each other.

It is a further object of the present invention to provide a spring construction having a plurality of outwardly bowed leaf springs in combination with second leaf springs engaging the mid portions of the first leaf springs in a manner to resist inward flexing thereof.

It is a further object of the present invention to provide a spring construction having a plurality of outwardly bowed leaf springs in combination with means interconnecting the ends of each of said leaf springs to the opposite ends of the adjacent leaf springs.

It is a further object of the present invention to provide a spring construction comprising a plurality of outwardly bowed leaf springs, each of said springs being formed throughout its length to provide a plurality of relatively short sinuous curves.

Other objects of the invention will be apparent as the description proceeds, and when taken in conjunction with the accompanying drawings, wherein:

Figure 1 is a transverse section through a seat back or cushion embodying my invention;

Figure 2 is a section on the line 2—2, Figure 1;

Figure 3 is a detail sectional view showing means for adjusting the tension of the coil springs;

Figure 4 is a diagrammatic view illustrating the tension adjusting means shown in Figure 3; and

Figure 5 is an elevation of a somewhat modified form of leaf spring.

Referring first to Figures 1 and 2 I have illustrated at 10 a frame, herein illustrated as being formed of sheet metal having its opposite sides bent to form end flanges 11 and inwardly extending flanges 12. It will be noted that the frame 10, together with the flanges 11 and 12 define inwardly open channels. The spring construc-

tion which forms the basis of the present application is carried by the frame 10 and is adapted to have suitable upholstery material secured thereover. In Figure 1 the upholstery material 5 is illustrated as comprising an inner pad 13 which may be formed of sisal, jute or the like, and an outer pad 14 which is preferably of some soft fibrous material, such for example as cotton. A trim fabric 15 overlies the cotton and provides the 10 wearing surface. The frame 10 is covered at its back with a panel board 16 which may if desired be covered with a suitable trim fabric 17. The fabrics 15 and 17 may, if desired be provided with suitable decoration and may be formed as 15 by sewing or otherwise to provide pleats.

The spring construction comprises essentially a plurality of leaf springs 30 having their ends bent to provide ears 31, together with coil compression springs 50 and intermediate secondary leaf springs 70.

In the channels provided by the frame 10 and the flanges 11 and 12 are provided a plurality of spring retaining cups 18, which may be soldered, welded or otherwise secured therein. The cups 25 18, together with the flanges 11 and 12 provide spring housings which are completely enclosed except for openings indicated at 19. More specifically the cups 18 are provided with stops 20 for a purpose subsequently to be described. The 30 coil springs 50 are received within the cups 18 and are adapted to engage the ears 31 of the leaf springs 30. As clearly shown in Figure 1, the ends of the leaf springs 30 extend through the opening 19 in the cups 18. As will be evident the coil springs 50 urge the ends of the leaf springs 30 inwardly in a manner to resist flexing thereof.

Auxiliary leaf springs 70 are provided which are bowed in the same direction as the leaf 35 springs 30, but on a shorter radius. The leaf 40 springs 70 engage and are preferably secured to the leaf springs 30 adjacent the mid portion thereof. The ends of the auxiliary springs 70 are bent as indicated at 71 to provide rounded bearing elements. Wear plates 72 are secured to the inner surface of the frame 10, and the ends 45 71 of the auxiliary springs 70 are in slidably contact with the wear plates 72. As will be evident, auxiliary springs 70 further tend to oppose inward flexing of the leaf springs 30. By properly 50 selecting the effectiveness of the springs 30, 50 and 70, it is possible to control the action or "ride" of the springs.

As best seen in Figure 2, the leaf springs 30 are interconnected by tension members, such as 55 wires 32. As will be noted, the wires 32 are

adapted to connect the ends of each leaf spring 30 to the opposite ends of both adjacent leaf springs. Wires 32 may be connected to the leaf springs as by welding or otherwise. As will be evident, the wires 32 tend to distribute the load in a manner to equalize the action of the springs. Thus, if a load is applied to a single leaf spring tending to reduce its curvature by inward flexing, the relative outward movement of the ends of the leaf spring is resisted by the inherent resilience of the leaf spring, the resilience of the corresponding auxiliary spring 70, the force of the compression springs 50, and the effect of wires 32.

As previously stated, the effectiveness of the 15 spring unit as a whole may be controlled by selecting springs 30, 50 and 70 having desired degrees of individual effectiveness. In some cases, however, it is desirable to vary the effectiveness of the spring unit as a whole, and for this purpose I provide the structure illustrated in Figures 3 and 4. In these figures I have shown the coil springs 50 as receiving the cup 18, which in turn is secured in the channel formed by the frame 10 and the flanges 11 and 12. In this instance, however, the coil springs 50 instead of abutting directly against the flanges 11, as illustrated in Figure 2, is provided with a floating plate 21 which extends along the channel previously referred to. It will be understood, of course, that the cup 18 is apertured to permit movement of the floating plate 21.

A shaft 22 is carried by the frame by suitable means (not shown), and secured at spaced points along the shaft 22 are a plurality of cams 23. The cams 23 may take the form of eccentrics on the shaft 22 and as will be evident, rotation of the shaft 22 will move the floating plate 21 inwardly or outwardly, thus varying the compression and effectiveness of the spring 50. I have illustrated means for manually adjusting the amount of rotation of shaft 22 as comprising a gear 24, keyed or otherwise secured to the shaft 22, in combination with a worm 25 carried by a shaft 26 which spans the channel formed by the frame 10 and flanges 11 and 12. The shaft 26 is provided with a manual adjustment knob 27. It has been found that adjustment of the tension of the springs 50 has a marked effect on the action of the spring unit as a whole.

While in the foregoing description I have illustrated the leaf springs 30 as being of uniform curvature, in some instances I prefer to employ a leaf spring 40 as illustrated in Figure 5. In this case the leaf spring 40 is initially formed with a plurality of short curves, as illustrated, so as to have a sinuously curved shape, as indicated in Figure 5. The ends of the spring 40 are bent to provide ears 41, similar in all respects to the ears 31 of the leaf springs 30 illustrated in Figure 1. Except for the initial formation into the sinuous shape, the spring 40 is identical with spring 30 and cooperates with the other elements of my combination in identical manner. The term "sinuously curved" is intended to define a leaf spring having a plurality of shallow corrugations, each of which has a greater dimension longitudinally of the leaf spring than its depth, as clearly shown in Figure 5.

While I have illustrated and described but one main modification of my invention, it will be apparent to those skilled in the art that various additions, modifications, omissions, combinations and substitutions may be made which 75

will be within the spirit and scope of my invention as defined by the appended claims.

What I claim as my invention is:

1. A spring construction comprising a frame 5 having opposing channels along opposite sides, a plurality of outwardly bowed leaf springs having their ends slideable in said channels, coil springs in said channels engaging the ends of said leaf springs and urging them toward each other, spring retaining cups in said channels for receiving said coil springs, said cups providing stops for limiting inward movement of the ends of said leaf springs.

2. A spring construction comprising a backing frame, a plurality of leaf springs mounted on said frame and bowed away therefrom, resilient means operatively associated with said leaf springs and opposing flexing of said springs toward said frame, and tie means interconnecting adjacent leaf springs for distributing load, said tie means comprising tension members interconnecting the opposite ends of adjacent members.

3. A spring construction comprising a backing frame, a plurality of leaf springs mounted on said frame and bowed away therefrom, resilient means operatively associated with said leaf springs and opposing flexing of said springs toward said frame, and tie means interconnecting adjacent leaf springs for distributing load, said tie means comprising tension members connecting one end of each intermediate leaf spring to the opposite end of each adjacent leaf spring.

4. A spring construction comprising a generally flat metal frame having its opposite edges bent to form opposed inwardly opening channels, a plurality of cups in said channels, coil compression springs in said cups, said cups having substantially closed inner ends provided with elongated openings, a plurality of substantially parallel outwardly bowed leaf springs extending across said frame, the ends of said springs extending through said openings into said cups, and into engagement with said coil springs, the ends of said leaf springs having abutments thereon engaging the closed inner ends of said cups to limit inward movement of said ends, a second leaf spring associated with each of said first leaf springs, said leaf springs engaging centrally of each other, said second leaf springs being bowed similarly to the bowing of said first leaf springs but on a shorter radius, the ends of said second leaf springs being slidably engaged on said frame, and tie wires connecting each end of said first leaf springs with the opposite end of each adjacent one of said first leaf springs.

5. A spring construction comprising a backing frame, a plurality of leaf springs mounted on said frame and bowed away therefrom, resilient means operatively associated with said leaf springs and opposing flexing of said springs toward said frame, said means comprising coil springs engaging the ends of said leaf springs, an adjustable abutment engaging all of said coil springs along one side of said frame, and cam means for adjusting said abutment to vary the effectiveness of all of said coil springs.

6. A spring construction comprising a backing frame, a plurality of leaf springs mounted on said frame and bowed away therefrom, resilient means operatively associated with said leaf springs and opposing flexing of said springs toward said frame, said means comprising coil springs engaging the ends of said leaf springs, an adjustable abutment engaging all of said coil

springs along one side of said frame, a plurality of cams engaging said abutment at spaced points therealong, a shaft connecting said cams for simultaneous movement, and manual means for adjusting the rotative position of said shaft.

7. A spring construction comprising a backing frame, a plurality of generally parallel leaf springs carried by said frame, said springs being bowed away from said frame and having their ends slideable thereon, and tie means interconnecting adjacent leaf springs for distributing load, said tie means comprising tension members interconnecting the opposite ends of adjacent leaf springs.

8. A spring construction comprising a backing frame, a plurality of generally parallel leaf springs carried by said frame, said springs being bowed away from said frame and having their ends slideable thereon, guides on said frame for guiding sliding movement of the ends of said leaf springs, abutment means limiting sliding movement of the ends of said leaf springs, and tie means interconnecting adjacent leaf springs for distributing load, said tie means comprising tension members interconnecting the opposite ends of adjacent leaf springs.

RUTHERFORD Y. MILLAR.
